UNITED STATES PATENT OFFICE.

GEORGE F. EARNSHAW, OF CHICAGO, ILLINOIS; ASSIGNOR TO EARNSHAW KNITTING COMPANY, A CORPORATION OF ILLINOIS.

INFANT'S BAND.

1,077,264.

Specification of Letters Patent.

Patented Nov. 4, 1913.

Application filed September 4, 1912. Serial No. 718,477.

To all whom it may concern:

Be it known that I, GEORGE F. EARNSHAW, a citizen of the United States, and resident of Chicago, in the county of Cook and 5 State of Illinois, have invented certain new and useful Improvements in Infants' Bands, of which the following is a specification.

This invention has reference to bands designed and adapted for infants' wear, these 10 bands being intended to afford protection to and maintain the warmth of the abdominal regions of small infants.

It is a well known fact that the heads of small infants are of approximately the same 15 width as their shoulders and, consequently, it is very difficult to keep a garment, which can be slipped on over the head, suspended from the shoulders. Bands have heretofore been employed which were provided 20 with shoulder straps, but these straps were necessarily spaced apart far enough to permit the band to be slipped on over the head, with the result that the straps would readily slip off from the shoulders and could not be 25 retained in position thereon.

One of the primary objects of the present invention is the provision of a band having the shoulder straps so formed that they will remain in place on the wearer's shoulders 30 but will permit the band to be slipped into position over the infant's head.

My invention will be readily understood by reference to the following description when considered in connection with the accompanying drawings illustrating one practical and preferred embodiment thereof.

Referring to the drawings—Figure 1 is a side view of a tubular fabric blank folded and cut to produce a band with attached shoulder straps; Fig. 2 is a front view of the band after the edges have been stitched and the strap fastening means have been completed; and Fig. 3 shows a completed band with the shoulder straps in the position that 45 they assume when on the wearer.

In order to afford the greatest protection against cold, bands of this character are customarily made of knitted material and, in the present instance, I employ a knitted 50 tubular fabric from which, by my improvement, a complete band may be produced without either longitudinal or transverse seams. The tubular fabric is first flattened longitudinally along median front and rear 55 lines and then both plies are simultaneously

cut to the shape shown in Fig. 1, providing a body portion 5, front and rear tabs 6 and 7 and a portion 8 extending upwardly from the body of the band along the rear median line. This extension is then divided along 60 the median line to produce two projecting portions 9 which form the shoulder straps. It will be observed from Fig. 2 that both of these straps rise from the center of the back so that when they are laid over the 65 infant's shoulders they will cling closely to the neck and will not separate and slide off from the shoulders as the ordinary shoulder straps do. The band is then preferably stitched around the edges to prevent raveling and to present a neat appearance and suitable slits or button-holes 10 are preferably worked in the ends of the shoulder straps to receive tapes 11 or other suitable fastening devices by means of which the 70 free ends of the shoulder straps are secured to the front of the band in position.

It will be manifest from the foregoing that I have provided a band, suitable for infants' wear, which can be readily slipped 75 on over the infant's head and retained in position by securing the straps disposed over the shoulders to the front of the band. By reason of the fact that the shoulder straps rise from the center of the back instead of from the sides thereof as in the ordinary 80 band, the straps are prevented from slipping off over the infant's shoulders and serve to retain the band snugly in position. When it is desired to remove the band the shoulder straps are unfastened, whereupon the 85 band can be slipped off over the wearer's feet without interference by the straps.

By my improvement the infant's band, including the straps, may be formed from 90 one piece of material, thereby obviating all seams which would be uncomfortable and very apt to chafe and injure the tender skin of a very young child.

It is believed that my invention will be 95 understood and its advantages will be appreciated from the foregoing without further description and, it will be obvious, that variations in the size, shape and proportion of the garment illustrated and described 100 may be resorted to without departing from the spirit of the invention or sacrificing any of the material advantages thereof.

I claim:

An infant's band comprising a sleeveless 110

and seamless continuous tubular knit body provided with a pair of integral extensions forming the shoulder straps disposed in close proximity to each other and extending upwardly from the central portion of the back thereof, said integral extensions being adapted to overlie the shoulders of the

wearer to form the sole suspension means, and means for securing the free end of said straps to the front of the body portion.

GEORGE F. EARNSHAW.
